APPARATUS FOR FITTING SHOES TO FEET

Daniel F. Hyland, John C. Stiles, Hugo L. Brenner, and John Brenner, St. Louis, Mo., assignors to Arch-O-Graph Company, St. Louis, Mo., a corporation of Missouri

Application March 13, 1941, Serial No. 383,092

10 Claims. (Cl. 12—60)

This invention pertains to apparatus for fitting shoes to feet and is adapted for carrying out the methods described in our copending application Serial No. 344,458, filed July 8, 1940.

One of the objects of this invention is to provide an apparatus whereby a model of the plantar surface of the foot may be taken with the foot in the same position that it normally occupies in a shoe when the wearer is standing, and forming from the model so taken off and from the shoe which is to be fitted to the foot a lift, said lift being so dimensioned as to occupy the space represented by the differences between the form of the inside sole surface of the shoe and the form of the plantar surface of the foot.

Another object is to provide such apparatus particularly adapted to take off an accurate model of a foot in the position occupied in a high-heeled lady's shoe.

Another object is to provide novel apparatus whereby a lift may be formed from the foot model and the shoe, but in inverted relation, so that the finished lift may be reinverted before placing in the shoe.

Further objects will appear from the following description of one embodiment of the invention, selected for illustration and explanation, said description being taken in connection with the accompanying drawings, in which:

Figure 1 is a plan view of an apparatus for forming lifts embodying this invention;

Figure 2 is a left-hand side view, partly in section, of the apparatus of Figure 1, but with the foot model device in place and adjusted for use;

Figure 3 is a front view of the apparatus shown in Figure 2 before adjusting the model device to operating position;

Figure 4 is a plan view of the device for taking off a model of the plantar surface of the foot;

Figure 5 is a side view of the device of Figure 4, but showing the same in adjusted position for taking a model of the foot;

Figure 6 is a detail of one of the feelers used in the model-taking device;

Figure 7 is an end view of a support for mounting the device of Figure 5 in position to take a model of the foot. This figure also shows the shoe-gauging device;

Figure 8 is a front view of Figure 7;

Figure 9 is a right-hand side view of Figure 1, somewhat enlarged;

Figure 10 is an enlarged detail of the stylus and its mounting;

Figure 11 is an enlarged sectional detail of the carriage supporting the operating arms; and

Figure 12 is an enlarged view of the gauge bar of Figure 8.

Referring now to the drawings, the apparatus illustrated in Figures 1, 2, and 3 comprises a supporting base 1 of any suitable form, which is provided with a movable platform or rack 2 upon which the model of the foot sole may be mounted, a second rack or support 3 upon which the shoe to be fitted may be mounted, and a holder indicated generally at 4 for the lift-blank. Suitable means may be provided, which will be described more in detail hereinafter, for properly positioning upon the supports 2, 3, and 4 the foot model, the shoe, and the lift-blank, so as to hold these devices in a predetermined relation with each other.

Mounted in the rearward portion of the base 1 is a carriage 5 carried on rollers 6, running on tracks 7. The lower face of each track 7 may be provided with a rack 8 engageable by pinions 9 on opposite ends of a shaft 10 journaled in the carriage 5. The shaft 10 provides a cross-connection between the racks 8, by which the carriage 5 is maintained in its original alignment, and so as to remain parallel to its original position at all points of its travel. The carriage 5 has journaled therein a shaft 11, which has fixed thereto a bracket 12 carrying an upright spindle 13. Pivoted on the spindle 13 for horizontal swinging movement is an arm 14 extending over the support 2, upon which the foot model is mounted. The arm 14 has mounted thereon on its front end a downwardly extending follower bar 15 adjustable vertically with respect to the arm 14 and equipped at its lower end with a ball tip 16 adapted for engagement with the model on the support 2. This structure is such that the bracket 12 carrying with it the arm 14 may hinge on the shaft 11 so as to permit vertical movement of the follower bar 15, while at the same time the arm 14 may swing horizontally on the spindle 13 so as to permit lateral movement of said follower bar. A fore and aft movement of the follower bar is permitted by movement of the carriage 5 along the tracks 7. This structure, therefore, provides for moving the follower in all directions over a three-dimensional model mounted on the support 2.

Also fixed upon the shaft 11 adjacent its other end is a bracket 17 carrying an upright spindle 18 upon which is mounted for horizontal swinging movement an arm 19 carrying at its end a forming element of any suitable type for performing a shaping operation upon a lift blank in the holder 4. In the embodiment illustrated, the

end of the arm 19 is equipped with an electric motor 20 whose shaft is provided at its lower end with a cutter 21 adapted to engage the lift-blank.

The hub of the arm 14 carries a pulley 22 secured thereto to rotate on the spindle 13 with the arm 14. The hub of the arm 19 carries a similar pulley 23 to rotate on the spindle 18 with the arm 19. The pulleys 22 and 23 are connected by a belt 24 passing around both pulleys. In the embodiment illustrated the belt 24 is crossed between the pulleys and is secured to each pulley by any suitable means such as a screw 25. The belt 24 is preferably a steel strip pulled taut between the pulleys, and functions to swing the arm 19 laterally in accordance with the lateral movement of the arm 14. By virtue of the crossed belt the movement of the arm 19 is reversed with respect to that of the arm 14 for a purpose which will be explained hereinafter. The arms 14 and 19 are preferably provided on the rear side of their pivots with counterweights 26 and 27, respectively.

Journalized in the carriage 5 to the rear of the shaft 11 and substantially parallel thereto is a second shaft 28, having fixed thereto a bracket 29 similar to the brackets 13 and 17 and carrying an upright spindle 30. Pivoted to swing laterally on the spindle 30 is an arm 31 extending forwardly over the shoe rack 3 and equipped at its forward end with a stylus 32 adapted to engage the inside sole of a shoe in the rack 3. The arm 31 may also be provided with a counterweight 33 in rear of its pivot. A link 34, best shown in Figure 1, is connected by ball-and-socket joints to the arms 14 and 31. This link 34 may be made adjustable as to its length by any suitable means such as screw sleeves 35. This link causes the arms 14 and 31 to move together in their lateral movement while permitting them to move independently in the vertical direction.

Fixed to the shaft 28 at the right-hand end thereof (Figure 1) is an arm 36 (see Figure 9) which passes underneath the blank holder 4 and is pivoted at its outer end at 37 on a slide 38 which slides in a fore and aft direction on a rod 39 secured in brackets 40 to the underside of the blank holder 4. By these connections the arm 36 serves to support the holder 4 and determine its elevation at any time. The holder 4 is further supported by a parallel motion comprising links 41 and 42 pivoted at 43 and 44, respectively, to the holder 4, and at 45 and 46 to the base 1. By this arrangement the links 41 and 42, of which there are two of each, as will be seen from Figures 1 and 9, serve to keep the holder 4 in level alignment while the arm 36 serves to determine its vertical position in accordance with that of the arm 31.

The general operation of this part of the mechanism may be outlined roughly as follows: With a model of the sole of the foot mounted on the support 2 and the shoe which is to be fitted to it mounted in the rack 3, a lift blank is secured in the holder 4. The details of these mountings will be more completely described hereinafter. The ends of the arms 31 and 14 carry, respectively, the stylus 32 and the follower 15 adapted to engage respectively the inner sole surface of the shoe and the surface of the model taken off the plantar surface of the foot. The fore-and-aft motion of both feelers is synchronized by the fact that they are carried upon the carriage 5 so that they move together in the fore-and-aft direction. Similarly, the arms 31 and 14 are connected by the link 34 so that their lateral swing-

ing movement is controlled so as to cause them to move together in the transverse direction also. Accordingly, as the stylus 32 is moved from point to point over the inner sole surface of the shoe, the follower 15, 16 is constrained to move to the corresponding points of the surface of the model. Accordingly, movements of the forming devices (which will be described presently), which are controlled respectively by the two elements 16 and 32, will at any one time correspond to the same point of the sole on the model and on the shoe sole.

Movements of the follower 16 in the vertical direction are duplicated by the forming tool 21. This follows, since movements of the arm 14 cause rotation of the shaft 11, which in turn causes corresponding vertical movements of the arm 19 which carries the tool 21. Similarly, vertical movements of the stylus 32 are carried through the arm 31 to cause rotation of the shaft 28 which imparts similar movements to the arm 36, causing the blank holder to rise and fall in exact correspondence with the rise and fall of the stylus 32.

It will be noted that the operation on the lift-blank in the holder 4 constitutes in effect simultaneous forming operations upon both faces of the blank. If the holder 4 were held stationary and the arm 36 carried a forming tool similar to the tool 21, it is easy to see that both upper and lower faces of the blank would be cut or otherwise formed at the same time, the upper face in a manner to correspond to the form of the model and the lower face to correspond with the form of the inner sole surface of the shoe. Accordingly, the resulting lift could be placed in the shoe and would be dimensioned at all points thereof to exactly the difference between the height of the model and the height of the sole of the shoe. However, in accordance with the present invention, the operation on the under-face of the lift blank as it rests in the holder 4 is modified to the extent that, instead of a cutting operation or one which changes the contour of that face of the blank, the holder is raised and lowered so that the elevation of that face as a whole is varied in accordance with the height of the inner sole surface of the shoe at any given point, while the tool 21 operates on the upper-face in accordance with the height of the model at the corresponding point. Accordingly, the thickness of the lift at this point will be equal to the difference between those heights. The advantage of this is that it leaves one face of the lift flat and makes it unnecessary to perform any operation thereon which will mar the surface of the blank on that face.

It will be noted, furthermore, that on account of the crossed relation of the belt 24, the arm 19 swings horizontally in the opposite direction to the movement of the arm 14. As a result of this arrangement, the upper face of the lift-blank, as it rests in the holder, will be formed with its contour reversed or left-handed with respect to that of the model. Accordingly, when the blank is finished, it may be inverted and in the resulting position its contour will match that of the foot from which the model was taken. It will be seen that this arrangement makes it possible to maintain that face of the lift-blank which engages the foot in a smooth and unaltered condition. In fact, a sock lining or similar finish may be put upon that face of the blank before it is operated upon, and will serve to provide a finish 75 for the inside of the shoe when the lift is finally

secured therein, in inverted position with respect to the one that it occupied in the holder 4.

Model take-off mechanism

In order to take off a model of the plantar surface of the foot, the mechanism shown in Figures 4, 5, and 6 may be employed. A frame or box 47, having a bottom 48 and side and end walls 49, is provided with one or more clamp bars 50, one or both of which may be movable with respect to the bottom and end walls. And mounted in vertical position between the side and end walls of this box is a series of shiftable feeler elements 51. These may be in the form of small square rods, such as shown in Figure 6, of any suitable material, such as steel or iron or even moldable plastic, and are positioned in parallel rows, as shown in Figure 4, and in engagement with each other so that they may be secured in shifted position by clamping. In order to provide for clamping these elements, one or more of the bars 50 may be lined with a thin layer 52 of cork or other yielding material, so that clamping pressure may be applied uniformly to the feelers. For this purpose clamping pressure may be exerted upon the movable side bars in any well-known manner, so as to clamp the elements 51. Between the elements 51 and the bottom 48 is a pad of resilient material 54 such as sponge rubber (see Figure 2). It has been found that the sponge rubber material prepared for mattresses, and having recesses therein so as to provide a considerable range of yieldability, gives very satisfactory results for this purpose. The elements 51 rest individually upon this yieldable material so that each may be depressed to any desired extent.

The model of the plantar surface of the foot is taken off by placing the foot upon the upper surface formed by the tops of all the elements 51 and placing just enough pressure upon the foot so as to depress these elements sufficiently so that each is shifted in accordance with the shape of the foot at the point which it engages. When the elements have thus been shifted, they may be secured in shifted position by clamping by means of the screws 53. In order to locate the model surface with respect to other portions of the machine, foot-locating plates are provided in connection with the box 47. A heel-locating plate 55 is provided with arms 56 which are pivoted upon a transverse rod 57. An inner alignment plate 58 is also arranged to extend vertically along the inner surface of the foot so as to align the same longitudinally, the device shown in Figure 4 being arranged for taking a model of the right foot. Accordingly, when the foot is placed with the heel against the plate 55 and the inner surface of the forward part of the foot against the plate 58, a model will be taken off which, while conforming with the shape of the foot, may afterward be located in the machine in proper correspondence with the shoe placed in the bracket 3.

Now, in order to provide what might be termed a zero level for the elements 51, a stop plate 59 is placed below the elements 51 at a portion of the model where the heel impression is made. The plate 59 is provided with downwardly extending flanges 60 by means of which it may be pivoted at 61 on a bracket 62 secured to the bottom 48. The pivot 61 fixes the level of that portion of the plate 59 just above it, while the plate may pivot so as to conform to the general slope of the heel surface when the impression is made. A thin layer 63 of rubber may be placed over the plate 59 so as to provide some resiliency in the

elements 51 thereabove. The rubber pad 54 is provided with a notch to pass around the bracket 62. As the forward limit of the lift is usually at the line where the ball of the foot begins, this part of the model may be fixed by providing a gauge plate 64 to receive the ball of the foot when the impression is made and to fix the level thereof in accordance with the shape of the shoe sole, as will be more fully described hereinafter. The plate 64 is supported by two pairs of pins, 43 and 44 respectively, extending outwardly from the sides thereof. The pins 43 rest in slots 45 in sliding pivot-brackets 69 (hereinafter described), and the pins 44 rest on other surfaces 15 of said brackets so as to support the plate 64 in general alignment with said brackets. The plate 64 may have its rear edge 65 cut at any suitable angle to conform to the shape of the ball of the foot. This plate 64 depresses the elements 51 20 therebelow so as in effect to get them out of the way and permit the ball of the foot to engage the plate 64, while other portions of the plantar surface engage the elements 51 which are moved into engagement with the foot under a resilient pressure by the pad 54. Accordingly, when the impression is thus being made, the height of the heel of the foot is controlled by the plate 59 and the height of the ball of the foot by the plate 64. Accordingly, the complete impression or model 25 not only conforms to the shape of the foot, but also assumes a general inclination in the box 47 in accordance with the setting of these plates 59 and 64.

In order to avoid the necessity of using a lift 35 blank of excessive thickness, it is desirable to align the blank with the general inclination of the surface of the model, or, vice versa, to align the model with the blank when mounted in the holder 4. At the same time, it is desirable to 40 align the inside sole surface of the shoe in the same manner with reference to the lift blank in order that its entire contour will fall within the limits of a blank of moderate thickness. In order to accomplish these purposes, provision is made 45 for setting the model at approximately the same inclination as that of the sole surface of the shoe as it is mounted in the rack 3, and then adjusting both the shoe and the model so that their surfaces are generally on a level with the lift blank in the holder 4.

The arrangements for accomplishing this purpose, so far as the model is concerned, are illustrated in Figures 4 and 5. A sub-base 66 is provided for the box 47, on which said box may be 50 mounted at any adjusted inclination. The sub-base 66 is provided with a pair of horizontal rods 67 supported in suitable end brackets 68 on the sub-base 66. Mounted to slide along the rods 67 are pivot brackets 69. Each of these brackets 60 receives a pivot pin 70, which is also pivoted in a slide 71 arranged to slide on a pair of rods 72, secured in the end brackets 49 of the box 47 and extending along the sides of said box, as will be seen from Figures 4 and 5. Thus, by means of 65 the pins 70 the box 47 is pivoted on the sub-base 66, and the pivot may slide longitudinally both with respect to the box and with respect to the sub-base. The clamp screws 53 and 53a are carried by the slides 71. At the forward end of the 70 box 47 the end bracket 49 is provided with pivot bearings 73, receiving pivot pins 74, which also engage similar pivot brackets 75 on an end support 76. The support 76 is fixed in cantilever relation to a vertical rod or pillar 77, slidably mounted in an upright guide 78. The pillar 77

may be fixed in the guide 78 by means of a clamping screw 79 whose inner end engages a groove 80 in the pillar. The inclination of the box 47 may be adjusted by raising the front end so as to cause the pillar 77 to slide vertically in its guide 78. At the same time, the box pivots at 70, while the pivot brackets 69 may slide along the rods 67. When the box has been adjusted to the desired inclination, the adjustment may be fixed by clamping the pillar 77 by means of the screw 79.

As the inclination to which the box 47 is adjusted, as just described, should be approximately the same as that of the inside sole surface of the shoe, gauging means are provided for taking off this inclination from the shoe and setting the box 47 in accordance therewith. Such gauging means are illustrated in Figures 7 and 8. A modeling rack 81 having platform 81a of any suitable type is provided with an upright heel stop 82 against which the shoe to be fitted, shown in dotted lines at 83 in Figure 7, may be placed. An upright column 84 is fixed on the platform 81, and a bracket 85 is arranged to slide on the column 84. The bracket 85 has fixed therein a downwardly extending gauge pin 86 of a suitable fixed length. This pin may be set to engage the inside sole surface of the shoe 83 at a given point of the heel, as shown in Figure 7. Mounted to slide horizontally in the bracket 85 is a bar 87, which has removably mounted at its end a fitting 88. A second gauge pin 89 is arranged to be slidably adjusted in the fitting 88 and may be clamped in adjustment by a suitable clamp screw 90. The pin 89 may be bent, as shown at 91, so as to clear the instep portion of the shoe, while the tip 92 of the pin is in vertical alignment with the upper straight shank portion thereof. The bar 87 may be provided with a scale, indicated at 93, to mark off the proper spacing between the pins 86 and 89 for different shoe sizes.

In taking off a gauge measurement by this device, the pin 86 is first set upon the heel surface, as already described. The bar 87 is adjusted in the bracket 85 to the proper shoe size by means of the scale 93. The pin 89 is then lowered until the tip 92 engages the inside of the sole, as shown in Figure 7, and this pin is then clamped by means of the screw 90. This adjustment provides a measurement on the pin 89 of the difference in elevation between the sole and heel portions of the inside of the shoe corresponding to the shoe size, as given on the scale 93. It will be seen that this gives a measurement of the average inclination of the shoe sole as indicated, for instance, by the line A—B.

In order to transfer this measurement to the setting of the box 47, the fitting 88 is slipped off the bar 87 without loosening the screw 90. The pin 89 is then transferred to the box 47 and slipped onto the end of a pin 94 secured to one of the slides 71, which is adjustable along the rods 72. This slide 71 is adjusted along the rods 72 until the pin 94 is spaced from the heel plate 55 on the box 47, a distance equal to the spacing of the pin 86 from the heel stop 82 minus the thickness of the shoe leather at that point. When so adjusted, the slide 71 is secured by a clamp screw 96. The other slide 71 (at the left, Figure 5) is now adjusted along the rods 72 so as to space the pin 70 from the pin 94, a distance equal to the spacing between the pins 86 and 89 when on the gauging device, shown in Figure 7, and the slide is then secured by a clamp screw 97. The fitting 88 having been en-

gaged with the pin 94, the gauge pin 89 is then brought into engagement with an index stop 98, the forward end of the box 47 being elevated until the gauge pin can be so set upon the stop 98. The stop 98 is spaced below the pivot 10 a distance equal to the length of the gauge pin 86. Accordingly, when this adjustment is made, the difference in elevation between the pins 94 and 70 will be the same as that between the tips of the pins 86 and 89 when gauging the shoe, as in Figure 7. Accordingly, when this adjustment has been made, the model surface will have the same general inclination as the line A—B of Figure 7. When used in the lift 15 forming apparatus in the manner just described, the fitting 88 and its associated pin 89 constitute means adjustable in accordance with the general inclination of the inner sole surface of the shoe for determining the inclination of the foot-sole modeling device. It will be noted that in this adjustment the plate 64 does not move with the box 47 but remains level so as to retain a position corresponding to the forward portion of the sole of the shoe 83 which is engaged by the ball of the foot. This adjustment of the box 47 to the inclination of the shoe is preferably made before the impression of the foot is taken. This places the plate 64 and the heel plate 59 in proper relation to each other so that the foot 20 impression may be taken by placing the heel against the plate 55, bringing the heel down until the pins 51 therebelow are stopped by the plate 59, and, at the same time, bringing the ball of the foot into engagement with the plate 64. The pins 51 may now be clamped, and when this is done, a correct model of the pantar surface of the foot will have been taken off. The heel plate 55 may pivot at 57 so that it may adjust 25 itself to the position of the heel of the foot when the impression is made.

Shoe rack and leveling mechanism

The base 1 is formed to provide an open horizontal frame 100 surrounding the shoe rack 3 and having downwardly extended side walls 101 and 102. The shoe rack, which is indicated generally at 3, is part of a cradle having a horizontal portion 103 provided with a plate 104 adapted to support the heel of the shoe. In rear of the portion 103 this cradle is formed with an open frame portion 105, which is traversed by a pair of supporting rods 106 which extend thereacross in a fore-and-aft direction and are supported in the frame 105. Mounted to slide on the rods 106 is a sole-supporting plate 107 provided with laterally adjustable stops or guides 108, movable along a rod 109 on the plate 107. These stops may be secured in any adjusted position by any suitable means, such as clamp screws 110. The shoe may be placed with its heel upon the plate 104 and the back surface engaging a heel stop 111. The heel may be secured by means of one or more clamp arms 112, which are mounted on guide rods 113 slidable in vertical holes in the plate 103 and tensioned by springs 114, surrounding these rods and bearing upon heads 115 thereon to pull the clamp hooks downwardly to retain the shoe.

The forward part of the shoe may rest upon the plate 107, being positioned laterally by the stops 108, and secured in position by a strap 116 secured to the plate 107 and arranged to pass over the toe of the shoe. This strap may be resiliently tensioned by a spring 117. The heel 70 of the shoe is centered against the heel plate

III, the side of the heel being brought into engagement with one or the other of stops 125 on the frame 100, according to whether the shoe is a right or left shoe. The forward part is located between the stops 108 which are adjusted laterally to give the shoe the proper alignment, the adjustment shown in Figure 1 being for a right shoe.

The cradle 103 has mounted in brackets 118 thereon a pair of supporting rods 119. These rods are slideable in brackets 120, pivoted at 121 on the side walls 101 and 102 of the main base. By this arrangement the cradle may pivot and slide with respect to the pivots 121. The forward part of the cradle has mounted in lateral extensions thereof a pair of vertically extending guide rods 122 arranged to slide in rotary brackets 123 pivoted on the shanks of clamp screws 124, which also serve to clamp the rods 122 against sliding movement. These rods thus provide guides serving to maintain the heel plate 111 in a constant alignment with the frame 100 during any rocking movement of the cradle on the pivots 121. During such rocking movement the cradle may move with respect to said pivots by sliding of the rods 119 in the brackets 120.

The cradle 103 has an angular arm 126 extending downwardly and then laterally to the left, Figure 3, passing through an opening 127 in the wall 101. The horizontally extending portion of this arm is formed into a platform providing the model rack 2, as shown in Figures 2 and 3. This platform is adapted to receive the sub-base 66, which may be secured in position thereon by any suitable means such as a clamp 128.

When a proper impression of the foot has been taken, as already described, and the shoe which is to be fitted to the foot is mounted in the rack 3, as just described, the inside sole surface of the shoe and the surface of the foot model as set up in the box 47 are brought into general alignment. For this purpose the rack 3 and the cradle 103 are so constructed as to bring the plates 104 and 107 into alignment with the plate 64 of the model (allowing for the thickness of the shoe sole), while the heel plate 111 of the shoe rack is so positioned as to bring the inside surface of the shoe at this point into alignment with the heel plate 55 of the model. However, in the position shown in Figure 5, these parts are not in alignment with the lift-blank in the holder 4. Accordingly, the cradle may now be rocked on the pivots 121 so as to bring these two surfaces into general alignment with the lift-blank. For this purpose a latch 129 is provided on the frame 100 positioned to engage and stop some portion of the box 47, such as the stud 130. When this adjustment is obtained, the inclination of the shoe surface as represented by the line A—B of Figure 7 is brought into general alignment with the lift-blank, in the manner indicated in Figure 2, in which the relative position of the lift-blank is represented roughly by the dotted rectangle C.

Lift-blank holder

The lift-blank is mounted in the holder 4. Any suitable type of blank and blank holder may be used. In the embodiment illustrated in the drawings, the lift-blank is indicated at 134. This blank may be constructed of cork or other suitable resilient, or semi-resilient, material. An effective form of blank is one comprising a sheet of cork about one-half inch thick, faced on one side with a sheet of suitable fabric,

leather, or other material. This material is preferably such as to be able to withstand a moderate amount of tension, and the blank may be provided with anchoring elements 135 at its ends, adapted to be engaged by suitable holding devices mounted in the holder 4 and arranged to apply endwise tension to the blank. These anchoring devices may be secured to the fabric facing so as to keep it stretched taut during the forming operation. The detail structure of the lift-blank and the lift holder are not a part of the present invention and are therefore not described in detail. Such a detailed description may be found in our copending application, mentioned above. In the illustrations of Figures 1 and 9 the blank is mounted in the holder with the facing down so that the forming tool 21 may operate on its uppermost face.

Resumé of operations

In accordance with this invention, therefore, the fitting of a shoe to a foot may be carried out as follows: The shoe is first gauged by means of the gauging device, shown in Figures 7 and 8, so as to take off a gauge setting on the pin 89, representing the general inclination of the shoe sole. The box 47 in which the model is to be taken off is then adjusted first by adjusting the slides 71 along the rods 72 in accordance with the shoe size in the same manner as the bar 87 was set according to shoe size. A scale 131 may be placed on one or both of the rods 72, or other suitable member for convenience in making this setting. The plate 64 having been placed into position, the gauge pin 89 may be applied to the pin 94 and the inclination of the box 47 set by resting said pin on the stop 98, after which the pillar 77 is clamped in position by means of the screws 79, as already described. This sets the box 47 at the same general inclination as that of the shoe sole.

For convenience in making the impression, the sub-base 66 may be placed upon the rack 81, which will hold the box 47 in a convenient position for applying the foot to make the impression. The rack 81 is provided with an inclined platform 136, upon which the sub-base 66 may be placed. The inclination of the platform 136 is preferably such as to set the box 47 at a convenient angle for applying the foot to be modeled thereto. An angle of about 30° to the horizontal has been found convenient. The end portion of the rack may be elevated and arranged to provide the platform 81, upon which the shoe may be placed so as to take the gauge measurements with the gauge bar 89, as already described. The foot to be fitted is then placed in engagement with the pins 51 with the heel against the heel plate 55 and the inside surface of the foot against the plate 58 and a side heel gauge 132, as shown in Figures 4 and 5, which represents a set-up for taking off a model of the right foot. The heel gauge 132 is mountable on either one of two pins 133, upstanding from the bars 50, according to whether a right or a left foot is being modeled. When a model of the left foot is to be taken off, a new plate 64 will be placed into position, shaped for the left foot instead of the right, and the gauge 132 is shifted to the upper pin 133, Figure 4. When the foot is properly positioned so as to depress the elements 51, the latter may be clamped by means of the screw 53, as already described, and said elements will then be positioned so that their upper ends provide a model of the foot to which the shoe is to

be fitted. It will be noted that in taking off this model the position of the foot may be adjusted to such a normal position as the foot should have when wearing the shoe, and, accordingly, the lift will be formed to the shape of the model of the foot in such position. For this purpose the patient may sit before the rack 81 in such position that the lower leg extends substantially at right angles to the inclined platform. This places the foot and leg in the same position with respect to said platform that they would have with respect to the ground when the patient is standing.

The shoe 83 is now transferred to the rack 3 and placed in position with the heel on the plate 104 and the inside of the heel against the stop 125. The forward part of the shoe will be located between the stops 108 and the inside of the heel against the stop 125 with the sole of the shoe placed to rest upon the plate 107. The strap 116 is passed over the toe of the shoe so as to hold the same in place, while the retaining arms 112 are let down upon the rear part of the shoe heel so as to clamp the same resiliently against the plate 104.

The sub-base 66, with the box 47 adjusted to its angular position, is now placed upon the platform 2 and suitably located and clamped in position thereon. The shoe and the foot model are now assembled upon the cradle in general alignment with each other. The cradle may now be rotated upon its pivots 121 until the stud 130 passes below the latch 129, to be located thereby, after which the cradle is clamped in position by means of the screws 124, which operate to clamp the rods 122 with respect to the frame 100.

In the embodiment illustrated a lift-blank made of cork or of similar material is contemplated. Other materials may, of course, be used, and the type of forming operation may, of course, be adapted to the material of which the lift is made.

With the shoe model and the lift-blank mounted in the machine, as described, the latter is then operated as follows: The motor 20 is started running so as to operate the tool 21. In the embodiment illustrated, this is a cutting tool and the operation will be described according to the operation of such tool, it being understood, however, that other types of forming elements may be employed with suitable modification in procedure.

The stylus 32 is placed into engagement with the inside sole surface of the shoe, starting at any convenient point such as the heel. The stylus is then manipulated by the operator so as to move its tip 152 over every portion of the inside sole surface.

It will be noted from Figure 10 that the stylus 32 has a bent shank so that its tip is offset with respect to the shank. This is in order to enable the tip to be inserted into the forward part of the shoe where the shoe upper would interfere with a straight shank. In order to make it possible to manipulate this feeler in all directions, the shank is mounted in a plate 153 secured to a shaft 154 journaled in a sleeve 155. The upper end of the shaft 154 has secured thereto a manipulating head 156. The sleeve 155 is threaded in a split bushing 157 so as to be adjustable vertically in order to adjust the height of the tip 152. This adjustment may be secured by clamping the split bushing upon the sleeve by means of a clamping screw 158. The bushing 157 is adjustably mounted upon a pivot 159 on the arm 31. These adjustments make it possible to set the tip 152

into exact correspondence with the tip 16 of the follower bar 15.

The tip 152 is then moved over the entire inner surface of the shoe sole. During such movement the link 34 will cause the arm 14 to move in an exactly corresponding manner over the surface of the model in the box 47. Accordingly, the tips 152 and 16 will always be at corresponding points of the shoe sole and the model.

Now, as the follower 16 moves over the surface of the model, the arm 14 will be caused thereby to rise and fall according to the height of the model surface. This rise and fall of the arm 14 causes the shaft 11 to rock, and such movement of the shaft in turn causes the arm 19 to rise and fall in exact correspondence with the rise and fall of the arm 14. Accordingly, the height of the forming tool 21 will always be in exact correspondence with the height of the follower 16 and, therefore, with the height of the model surface at the point engaged by said follower. As the tool 21 operates upon the lift blank, the latter will be cut or formed to a height corresponding exactly to the height of the model at the corresponding point thereof. As the follower 16 moves over the surface of the model, therefore, the tool 21 will operate to form the lift-blank to the same contour as that of the model.

As the stylus tip 152 moves over the sole surface 30 of the shoe, its elevation changes in accordance with the contour of that surface. The corresponding rise and fall of the arm 31 operates through the shaft 28 to cause a corresponding rise and fall of the arm 36, which controls the height 35 of the blank holder 4. Accordingly, at every point at which the tool 21 is operating, the height of the blank will correspond exactly with the height of the inside sole surface at the corresponding point thereof. It will be seen, therefore, 40 that since at any given point of operation of the tool 21 the height of said tool corresponds with the height of the model surface, while the elevation of the blank corresponds to the height of the shoe sole surface, the thickness to which the lift is formed at that point will correspond to the difference between said heights. This difference is exactly the difference between the contour of the foot in normal position and the contour of the inside surface of the shoe. Accordingly, 45 a blank will be formed so as to occupy exactly the space representing this difference between the contour of the foot sole and the contour of the shoe sole.

In the embodiment illustrated in Figure 9, the 55 tool 21 is shown as a cutting tool. Accordingly, the holder 4 is provided with a downwardly extending connection 160 communicating with the suction pipe 161, connected to a suction blower 162, adapted to carry off the cuttings. A suitable cover may be placed over the holder 4 if desired to prevent the cuttings from being projected into the room.

As shown in Figure 11, the shafts 28 and 11 may be provided, respectively, with downwardly extending arms 163 and 164. One of these arms may be provided at its lower end with an adjustable stop 165 secured by a nut 166 and adapted to engage a stop face 167 on the other arm. This arrangement limits the rotation of the shafts 70 28 and 11 in such a manner as to prevent the arms 19 and 36 from approaching close enough to each other to cut entirely through the lift blank. Accordingly, a minimum thickness is established 75 below which the tool 21 will not operate. Accord-

ingly, the lift may be cut down practically to the sock liner without cutting through the same.

When the lift has been properly formed, as above described, over the entire surface thereof, the same may be trimmed to the proper outline in accordance with the size of the shoe involved. When so formed, the lift may be treated with adhesive on the formed side and inverted and placed in the shoe to be secured therein. It will be recalled that by the operation of the crossed belt 24, the movement of the arms 14 and 19 is reversed with respect to each other, and, accordingly, the lift is formed in left-handed relation to the model. This relation is again reversed when the finished lift is inverted to be placed in the shoe, so that the correct lift for the right foot is obtained as a result.

While this invention has been described as embodied in a unitary apparatus, it will be understood that individual features or sub-combinations thereof may be found useful without other features or the complete combination.

It is understood, therefore, that the employment of such individual features or sub-combinations is contemplated by this invention when within the scope of the appended claims.

It is also pointed out that various changes in the details of construction may be made within the scope of the appended claims without departing from the spirit of this invention, and that therefore the invention is not limited to the specific details shown or described.

The invention having thus been described, what is claimed is:

1. In an apparatus of the character described, a foot-sole modeling device, supporting means for said device, means for adjusting said device on said supporting means so as to position its sole-modeling surface in accordance with the position of the foot sole when standing in a shoe having a heel, lift-forming means having a lift-blank holder, a shoe holder, means for mounting said device assembled on its supporting means in cooperative relation with said shoe holder and said blank holder, means for positioning said mounting means and said shoe holder so as to position the modeling surface of said device and the inner sole surface of a shoe in said shoe holder in accordance with the position of a blank in said blank holder, and control mechanism for said forming means having guiding means engaging said sole-modeling surface and the inside sole surface of a shoe in said shoe holder.

2. In an apparatus of the character described, a foot-sole modeling device, a shoe holder, a lift-blank holder, angularly adjustable means for mounting said device and said shoe holder in cooperative relation with said blank holder, means associated with said mounting means for angularly positioning said device and said shoe holder in accordance with the position of a blank in said blank holder, lift-forming means cooperatively associated with said blank holder, and control mechanism for said forming means having guiding means engaging the modeling surface of said device and the inside sole surface of a shoe in said shoe holder.

3. In an apparatus of the character described, a foot-sole modeling device having a level abutment for the ball of the foot and a modeling surface adjustable in accordance with the inclination of the foot-sole when standing in a shoe having a heel, a shoe holder, a lift-blank holder, means for mounting said device and said shoe

holder in cooperative relation with said blank holder, means associated with said mounting means for positioning said modeling surface of said device and the inside sole surface of a shoe in said shoe holder in accordance with the position of a blank in said blank holder, lift-forming means cooperatively associated with said blank holder, and control mechanism for said forming means having guiding means engaging the modeling surface of said device and the inside sole surface of a shoe in said shoe holder.

4. In an apparatus of the character described, a foot-sole modeling device, a shoe holder, a lift-blank holder, means for mounting said device and said shoe holder in cooperative relation to said blank holder including a cradle carrying said device and said shoe holder and adjustable to position the same to correspond with said lift-blank holder, and lift forming means guided by said device and a shoe in said shoe holder to form a lift in said blank holder.

5. In an apparatus of the character described, a foot-sole modeling device, means for gauging the inclination of the inside sole surface of a shoe, means cooperatively associated with said gauging means for adjusting said modeling device to a corresponding inclination, lift-forming means having a lift-blank holder, and means for positioning said modeling device, as adjusted, in accordance with the position of a blank in said holder.

6. In an apparatus of the character described, a foot-sole modeling device, means for gauging the inclination of the inside sole surface of a shoe, a holder for the gauged shoe, means cooperatively associated with said gauging means for adjusting said modeling device to a corresponding inclination so as to position it to correspond with the position of the shoe in said shoe holder, lift-forming means having a lift-blank holder, and means for positioning said modeling device and the shoe in said shoe holder to correspond with the position of a blank in said blank holder.

7. In a machine of the character described for fitting shoes to feet having a lift-blank holder, forming means adapted to operate on a blank in said holder and control means for said forming means; a support having a shoe holder, means for receiving a foot-sole modeling device, and means for adjusting said shoe holder and said receiving means relatively to position the modeling surface of said device and the inside sole surface of a shoe in said shoe holder to the same general plane, said support also having means for adjusting the same relatively to said blank holder to adjust said plane to that of said blank holder.

8. In an apparatus of the character described for fitting shoes to feet, a foot-sole modeling device, a shoe holder, a lift-blank holder, means for positioning said device with its modeling surface at the same general inclination as that of the inner sole surface of the shoe to be fitted in order that the foot impression is at the same inclination, means cooperating with said positioning means for mounting said device in cooperative relation with said shoe holder and said blank holder and with its modeling surface at the same general level as that of a lift-blank in said blank holder and the inner sole surface of a shoe in said shoe holder, lift-forming means cooperatively associated with said blank holder, and control mechanism for said forming means having guiding means engaging the modeling

surface of said device and the inner sole surface of a shoe in said shoe holder.

9. In an apparatus of the character described for fitting shoes to feet, a foot-sole modeling device, a shoe holder, a lift-blank holder, means adjustable in accordance with the general inclination of the inner sole surface of the shoe for determining the inclination of the foot-sole modeling device, means for mounting said device in cooperative relation with said shoe holder and said blank holder cooperating with said adjustable means to adjust the modeling surface of said device to the same general level as that of a lift-blank in said blank holder, lift-forming means cooperatively associated with said blank holder, and control mechanism for said forming means having guiding means engaging the modeling surface of said device and the inner sole surface of a shoe in said shoe holder.

10. In an apparatus of the character described for fitting shoes to feet, a foot-sole modeling device, a shoe holder, a lift-blank holder, means adjustable in accordance with the general inclination of the inner sole surface of the shoe for determining the inclination of the foot-sole modeling device, an angularly adjustable support for said device, additional means controlled by said adjustable means for setting said support angularly so as to position the modeling surface of said device in cooperative relation with said blank holder, lift-forming means cooperatively associated with said blank holder, and control mechanism for said forming means having guiding means engaging said modeling surface.
